RIDER STEERED POWER LAWN MOWER

Orly Musgrave, Springfield, Ohio

Application July 1, 1955, Serial No. 36,792

Term of patent 14 years

(Cl. D40—1)

Figure 1 is a perspective view of a rider steered power lawn mower embodying my new design;

Figure 2 is a right side elevational view thereof;

Figure 3 is a left side elevational view thereof;

Figure 4 is a plan view of the design of Figures 1-3;

Figure 5 is a front elevational view of the design of Figures 1-4; and

Figure 6 is a rear elevational view of the lawn mower.
I claim:

The ornamental design for a rider steered power lawn mower, substantially as shown.
